CLAIM

The ornamental design for a basketball stand, as shown and described.

DESCRIPTION

FIG. 1 is a front perspective view of a basketball stand showing my new design;

FIG. 2 is a back perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the encircled portion 9 in FIG. 1;

FIG. 10 is an enlarged view of the encircled portion 10 in FIG. 1;

FIG. 11 is an enlarged view of the encircled portion 11 in FIG. 1;

FIG. 12 is an enlarged view of the encircled portion 12 in FIG. 1;

FIG. 13 is an enlarged view of the encircled portion 13 in FIG. 2;

FIG. 14 is an enlarged view of the encircled portion 14 in FIG. 2;

FIG. 15 is an enlarged top view thereof; and,

FIG. 16 is an enlarged view of the encircled portion 16 in FIG. 7.
